UNITED STATES PATENT OFFICE

LOUIS E. GOLDBLATT, OF BROOKLYN, NEW YORK

STRETCHER

Application filed June 19, 1931. Serial No. 545,444.

This invention relates to stretchers and is particularly directed to apparatus for transporting patients, such as orthopneic patients, in sitting posture.

5 An object of this invention is to provide apparatus of the character described for effectively retaining in upright position, the upper portion of the person's body, while being transported, whereby patients who can 10 only breathe in upright or sitting position and whose life would be endangered by placing the patients in prone position, may be safely transported as for example, to a hospital.

15 Another object of this invention is to provide apparatus of the character described which shall be readily collapsible, so that the flexible portions thereof may be readily removed for the purpose of washing and sterilizing; and which may be readily and quickly set up, for example, in the street, for carrying a patient from the scene of an accident directly to a hospital bed with the upper portion of his body in upright position.

20 25 A further object of this invention is to provide a compact and durable apparatus of the character described which shall comprise comparatively few and simple parts, be easy to set up or collapse, which shall be comfortable and safe in use and easy to handle for carrying patients, and which shall be comparatively inexpensive to manufacture, and withal practical and efficient to a high degree.

30 35 Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

40 45 In the accompanying drawing, in which is shown one of the various possible illustrative embodiments of this invention,

50 Fig. 1 is a perspective view of apparatus embodying the invention in position for receiving the patient;

Fig. 2 is a longitudinal, vertical cross-sectional view of the structure shown in Fig. 1;

Fig. 3 is a top plan view of a portion of my improved apparatus with parts thereof folded; and

Fig. 4 is a perspective view of the frame used in my improved apparatus and showing a portion thereof in horizontal position in dotted lines.

Referring now in detail to the drawing, 50 55 60 65 70 75 80 85 90 95 100 105 110 115 120 125 130 135 140 145 150 155 160 165 170 175 180 185 190 195 200 205 210 215 220 225 230 235 240 245 250 255 the strap attached for retaining the patient in sitting position on top of the sleeve 16, and with the patient's legs outstretched.

For retaining said portion 19 in upright position there is provided a frame member 30, preferably made of hollow tubing, and comprising a portion 31 adapted to be placed on the stretcher 11 adjacent the portion 19, and a portion 32 hinged to said portion 31 and having a pair of upright members 34 and 35 adapted to extend through said sleeves 22, 22a. Preferably, said frame portion 31 is provided with upright portions 36 and 37 of channel cross-section for receiving the lower end portions of the uprights 34, 35. Said uprights may furthermore be pivoted as at 39 and 40 to said portions 36 and 37, respectively, whereby the member 32 may be swung downwardly to the dotted line position shown in Fig. 1, for convenience in storing the frame. Obviously, the channel shaped portions 36, 37 are adapted to retain the member 32 in upright position and to limit the upwardly swinging movement thereof to the position shown in full lines in Fig. 4. To give added strength, a member 41 may interconnect the upright members 34, 35, adjacent the lower ends thereof.

For retaining the frame member in position on the stretcher, there is provided a member 44 made of canvas or any other suitable textile material stitched to said edge portions 17, as at 45, and extending rearwardly therefrom. The member 44 is preferably provided with outward extensions 46 and 47 adapted to be folded over the sleeve portion 14 of the stretcher 11. Attached to said extensions 46 and 47 are strap portions 48 and 49 respectively, one of said portions having a buckle 48a, and the other of said portions having a row of perforations 49a for coaction with said buckle, whereby said extensions 46 and 47 may be folded to overlie the portion 31 of the frame member 30 and strapped together for preventing tilting of the frame member. Obviously, any other suitable fastening means may be substituted for the buckle and strap described above.

It will now be seen that a patient, such as any orthopneic patient, who can only breathe in upright or sitting position, may be placed on top of the member 16 with the patient's back against the member 19 and the legs outstretched. The portions 26 and 27 may thus be strapped together for tightly retaining the patient in said position and to prevent the patient from moving. Upon lifting and moving the stretcher by means of the poles 15, the stretcher will naturally curve somewhat about the patient's legs, and thighs and due to the strapping of the patient, the patient will not fall from the apparatus during transit, even though the stretcher is tilted sidewise. The upper portion of the patient's body will be retained in upright po-

sition since the frame member cannot tilt rearwardly by reason of the channel shaped portions 36 and 37 of the frame member. When a patient is carried in my apparatus, the poles 15 press against the sides of the frame and they serve to retain said frame against movement.

It will further be noted that when the apparatus is not in use, the stretcher portion 11 may be removed from the member 12 and the frame member may also be removed and folded into a single plane. The member 12 being made of canvas or the like textile material, may also be folded into a compact package and may furthermore be readily washed and sterilized. Obviously, if desired, the sleeve portion 16 may be shortened so that the patient's legs will rest directly on the portion 13 of the stretcher. Also the rod portion 41 may be curved to conform to the natural curvature of the patient's back. The upright rods 34, 35 may furthermore be tapered outwardly for adding to the comfort of the patient.

My improved apparatus may be readily carried in an ambulance and set up in the street at the scene of an accident, or wherever the patient may be, so that the patient may be directly placed on my improved stretcher and retained with the back upright until the patient reaches the hospital bed.

As shown in Fig. 1, the upper portion of sleeve 16 may be slit transversely as at 50 for receiving the patient's legs, said sleeve thus serving to retain the legs against movement. The forward ends of the poles may be moved together for pouching of the sleeve 16 sufficiently to permit the patient's legs to be passed within said sleeve.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:

1. In combination with a stretcher comprising an elongated flexible sheet having parallel sleeves at the side edges thereof, and poles within said sleeves and extending from the outer ends thereof and forming handles for carrying the stretcher, said stretcher being adapted to support a person lying thereon, and means on said stretcher for retaining the upper portion of the body of a person carried on said stretcher in upright position, said

means comprising a frame having a portion resting on said flexible sheet and between said poles, and an upright portion pivoted to said first portion and having a pair of parallel up-standing arms, a flexible sleeve disposed about said stretcher, straps extending from said sleeve disposed about said first portion of said frame for attaching said frame to said stretcher, and a flexible back-rest having 10 sleeve portions at the ends thereof for removably receiving said arms.

2. In combination with a stretcher, means for retaining the upper portion of the body of a person lying on said stretcher in upright position, said means comprising a frame member having a portion resting on said stretcher, and an upright portion pivoted to said first portion, a flexible sleeve member removably receiving said stretcher and having straps 20 disposed about the first portion of said frame for attaching said frame to said stretcher, and a flexible member removably attached to said upright portion forming a back-rest.

3. In combination with a stretcher, means 25 for retaining the upper portion of the body of a person carried on said stretcher in upright position, said means comprising a sleeve-like member receiving said stretcher therethrough and a frame member having a portion resting on said stretcher and an upright portion, a flexible member extending from said sleeve-like member forming a back rest attached to said upright portion, and means on said back rest for strapping the 35 patient's body thereto.

4. In combination with a stretcher adapted to support a person lying thereon, means detachably attached thereto for retaining the patient carried on said stretcher with his 40 back in substantially upright position, said means comprising a frame removably mounted on said stretcher, a flexible member forming a back rest attached to said frame, means on said back-rest for strapping the patient's 45 back thereto, means for attaching said frame to said stretcher, and means extending from said last mentioned means for attaching the patient's legs to said stretcher.

5. In combination, a stretcher comprising 50 an elongated flexible sheet having parallel sleeves at the side edges thereof and poles within said sleeves and extending from the outer ends thereof and forming handles for carrying the stretcher, a sleeve receiving said 55 stretcher therethrough, a frame having a portion resting on said stretcher and an upright portion, and a member extending from said sleeve attached to said upright portion and forming a back rest.

6. In combination with a stretcher comprising an elongated flexible sheet having parallel sleeves at the side edges thereof, and poles within said sleeves and extending from the outer ends thereof and forming handles 65 for carrying the stretcher, a sleeve receiving

said stretcher therethrough, a frame having a portion resting on said stretcher and an upright portion, and a member extending from said sleeve attached to said upright portion and forming a back rest, and means 70 attached to said extending member for strapping a patient's body to said stretcher.

7. In combination with a stretcher comprising an elongated flexible sheet having parallel sleeves at the side edges thereof and 75 poles within said sleeves and extending from the outer ends thereof and forming handles for carrying the stretcher, a sleeve receiving said stretcher therethrough, a frame having a portion resting on said stretcher, and an 80 upright portion, and a member extending from said sleeve attached to said upright portion and forming a back rest, and means for strapping the first named portion of said frame to said stretcher.

In testimony whereof I affix my signature.
LOUIS E. GOLDBLATT.
